George Hergeshimer } Inventor

United States Patent Office.

GEORGE HERGESHEIMER, OF PHILADELPHIA, PENNSYLVANIA, ASSIGNOR
TO HIMSELF AND CORNELIUS V. FORT, OF SAME PLACE.

Letters Patent No. 74,224, dated February 11, 1868.

IMPROVED BRUSH-BRIDLE.

The Schedule referred to in these Letters Patent and making part of the same.

TO ALL WHOM IT MAY CONCERN:

Be it known that I, GEORGE HERGESHEIMER, of the city and county of Philadelphia, and State of Pennsylvania, have invented a new and improved "Brush-Bridle," and I do hereby declare that the following is a full, clear, and exact description of the construction and operation of the same, reference being had to the accompanying drawings, making a part of this specification, in which—

Figure 1 is a perspective view of a brush with my bridle attached.

Figure 2 is a perspective view of a brush with my bridle attached, but made in a different form.

Figures 3 and 4 are views of my bridle detached from the brushes.

The object of my invention is to overcome the difficulty experienced by painters and others in regulating the stiffness of the bristles of their brushes, and, at the same time, to obtain proper flexibility, which cannot be done by the present process of bridling with twine or wire without great loss of time. It is also to prevent brushes from becoming foul, or the dropping of paint from the brush.

To enable others skilled in the art to make and use my invention, I will now proceed to describe its construction and operation.

I make my bridle in two forms—A and B, figs. 3 and 4. Bridle A is made in a circular form, and of vulcanized or soft rubber, of a thickness of about one-sixteenth of an inch, the length and diameter of a sufficient size to suit the brush to which it is to be applied. Bridle B is made of the same material and in the same manner, with the exception that, at the lower end, I form a suction-cup, S C, and flange, F L, to catch the paint or other material, when the brush is being used, in a position to cause it (the paint) to flow towards the handle.

When a brush is procured new, it has to be bridled from one to one and a half inch below what is called by the trade the made part of the brush. This is now done by twine. Now, it becomes necessary, when the brush is in constant use, to unbridge and bridge twice a day. If this is neglected the brush mats and fouls, and, in a short time, wears out in the centre and becomes useless. Another inconvenience is the continual change necessary to regulate the brush to the style of painting, some work requiring a stiff and other a loose brush, therefore causing great inconvenience and loss of time, by the bridling and unbridling, to regulate it. All this I entirely overcome.

Another advantage of my invention is the spring given to the brush, and the expansion allowed by the elasticity of the rubber. When a brush has been used, and left over night without cleaning, the water in which the brushes are allowed to remain swells the twine, and draws the bristles up tight, and makes the brush hard and difficult to clean.

The advantages of the above-described suction-cup S C and flange F L are obvious. In painting ceilings, or work where it is necessary to have the brush at a higher point than the handle, the paint is apt to run down the handle of the brush and drop off on the floor or carpet. Now, by my arrangement, the material will fall on flange F L, and thence flow into cup S C, and remain until the bridle is removed.

In applying the bridle, the handle of the brush is inserted, and the bridle drawn down over the shoulder, until it assumes the position shown in figs. 1 and 2, the stiffness of the bristles being regulated by raising or lowering the bridle.

Having thus described my invention, its construction and operation, what I claim as new, and desire to secure by Letters Patent of the United States, is—

The arrangement of brush-bridle B, with the suction-cup S C and flange F L, constructed and operating in the manner and for the purpose as herein set forth and described.

GEORGE HERGESHEIMER.
